[57] CLAIM

The ornamental design for a bearing, as shown and described.

DESCRIPTION

FIG. 1 is a top plan view of a bearing showing an embodiment of our new design, the bottom plan view being the same in appearance;

FIG. 2 is a front elevational view thereof;

FIG. 3 is a right-hand side elevational view thereof and is also a mirror image of a left-hand side elevational view thereof;

FIG. 4 is a rear elevational view thereof; and,

FIG. 5 is a perspective view thereof.
